OIL WELL PACKER

Joseph Rockoff, Dayton, Ohio, assignor to The Dayton Rubber Company, a corporation of Ohio

Application November 1, 1946, Serial No. 707,087

15 Claims. (Cl. 166—10)

1

This invention deals with expansion members such as packers, and in particular with oil well packers.

It is an object of this invention to provide packers for oil wells which are chemically resistant to oil.

It is another object of this invention to provide oil well packers which are resistant to high temperatures and in particular to hot oil.

It is another object of this invention to provide oil well packers which have a high resistance to abrasion on their surface layers.

It is another object of this invention to provide oil well packers which are extremely strong and durable.

It is still another object of this invention to provide oil well packers which have a high lateral expansibility.

It is still another object of this invention to provide oil well packers which, after cessation of the expansion causing pressure, fully recover their original shape and dimensions.

It is still another object of this invention to provide oil well packers which have a high degree of stiffness in the portions adjacent the edges and ends, so that no flow of rubber will occur there under the pressure applied.

It is still another object of this invention to provide oil well packers which have a long service life and may be used for a great number of times.

The invention will be fully understood from the following description taken in connection with the accompanying drawings, in which

Figures 1, 10, 11 and 12 illustrate in elevational views various uses of oil well packers;

Figure 2 is a view partly in section and partly in elevation, of an oil well packer of my invention;

Figure 3 is a cross sectional view taken along line 3—3 of Figure 2;

Figure 4 is a cross sectional view taken along line 4—4 of Figure 2;

Figure 5 is a perspective view of a mandrel on which the packer is built up;

Figure 6 shows a fabric preferred for the packer of my invention;

Figure 7 is a view partly in elevation and partly in cross section showing one end of a packer built up on a mandrel in accordance with the present invention;

Figure 8 is a perspective view of one of the reinforcement rings used at each end of the packer; and

Figure 9 is a perspective view of the same rein-

2

forcement ring of Figure 8, as viewed from the other end thereof, after an end layer has been applied thereto.

Referring now to Figure 1 in particular, there is shown a packer 10 having the retaining collars or shoes 11 and 12 at its ends and being fastened to an anchor pipe 13. While in Figure 1 the packer is shown in its original dimensions, Figure 10 shows it under the influence of compressive forces which effect the expansion of the packer 10 and thereby the sealing of the well. Figure 11 shows the use of the combination of two packers 14 and 15 in a well and Figure 12 that of a packer 16 in combination with a cone packer 17 composed of a plurality of rings.

One embodiment of a packer of my invention is illustrated in detail in Figures 2 to 4; there the packer is generally designated by the reference numeral 18. The reference numeral 19 indicates an inner casing which terminates in a flange 20 having bores for studs 21 which are secured with nuts 22. An outer casing 22 is arranged concentrically with regard to said inner casing 19; this outer casing has a flange 23 at which it is fastened to the packer 18 by means of studs and nuts 24. The packer proper consists of an innermost layer 25 which is composed of a plurality of plies of rubber-impregnated fabric material. The bottom end of the packer is illustrated in cross section in Figure 2; the upper end of the packer is made with identical structure. On each end of the packer, there is placed a metal ring 27 over said layer 25, and a heavy rubber layer 26 is applied over the layer 25 so as to fill out the space between said two metal rings. Thereover, another layer 30 of a number of rubberized fabric plies is applied. The metal ring 27 is provided with a shoulder 28 on the outer end and a lip 29 at the inner end. Due to these features and due to the fact that the fabric plies forming layer 30 are applied under tension, the metal ring 27 and the rubber layer 26 are firmly anchored. At the place where the cylinder formed by the fabric plies forming layer 30 decreases in diameter due to the lip of the metal ring, metal wires 31 are wound over said fabric layer 30 so as to give the various layers a secure fit on the ring 27. Two plies of rubberized fabric 32 are then placed on top of these wire windings. The ends of the packer each have an end portion 33 which is also formed of rubberized fabric. The outer surface of the packer is formed of a layer 34 consisting exclusively of rubber material.

All of the rubberized fabric layers may be re-

placed by rubberized cord layers. It is essential that the textile material, whether cord or fabric, has a high tensile strength and elasticity. In order to obtain this result, especially high elasticity, twisted cords may be used. An especially satisfactory material is nylon which combines both elasticity and high tensile strength. In the case of fabric layers, it is advantageous to apply the fabric in an angle of 45° because the highest degree of stretchability possible is then obtained. It is also helpful to use a fabric which is woven from twisted cords and preferably from twisted nylon cords (nylon is the name commonly applied to a synthetic fiber which is a polyamide having a protein-like structure). Furthermore, the lateral stretchability can still be increased by using relatively thin cords for the cross threads and cords of regular thickness for the lengthwise threads. By this, the longitudinal strength is retained while the lateral flexibility and expansibility are considerably increased. Still another means for increasing the lateral expansibility of the packer is to subject the fabric or the cords to a preshrinking process prior to their use in building up the packer.

While practically all rubber materials, in particular synthetic rubbers, are usable for the packers of my invention as long as they are oil resistant, it is preferred to use neoprene therefor. The synthetic rubber-like chloroprene polymer commonly known as neoprene has all properties desired for a packer, in particular high resistance to oil, to abrasion and excellent bonding property with metals. It was also found advantageous to use a softer rubber for impregnating and bonding the various inner layers and to select a relatively harder rubber composition relatively hard by comparison with the rubber used for the inner layers for building up the outermost and top surface layers 33 and 34. By this, flow of the rubber during application of expansion causing pressures and thus deformation of the packer are prevented.

Figures 5 to 9 illustrate the process of manufacture of a packer of my invention, but of an embodiment different from that of Figures 2 to 4. There, the reference numeral 35 indicates a mandrel, for example a steel mandrel, on which the various layers are built up. First several layers of rubberized fabric 36 are wound on the mandrel 35. Figure 6 shows the fabric used therefor; it is on a bias and is woven from thin cross threads 37 and relatively heavy longitudinal cords 38. As stated above, it is advantageous to apply the fabric at an angle of 45 degrees, or in other words, the fabric is applied in such a manner that the threads which run in one direction are at an angle of 45 degrees to the longitudinal axis of the sleeve. Over this fabric layer 36 there is then applied a layer 44 which consists of a relatively soft rubber material. This rubber layer 44 does not extend entirely to the ends of the mandrel, but enough space is left so that a metal ring 39 may be placed at each end of the mandrel. Figures 8 and 9 show the construction of the rings as they are applied to the end portions over the fabric layer 36. The rings have been previously combined with an end layer 42 which consists of fabric material impregnated with a relatively hard rubber. The rings 39 which have one inwardly tapered end surface 40 decreasing in diameter from the outer surface to the inner surface to form the lip responsible for firm anchorage and for preventing the flow of rubber

and which also have a shoulder 41 at the other end for the same purpose, are combined with the end piece 42 by means of screws 43. After insertion of the metal rings, another layer of rubberized fabric 45 is wound over the rubber layer 44 and the rings 39. Steel wire and rubberized fabric layers (not shown) are then wound over said rubberized fabric layers 45 to fill out the recess formed between the lip 40 and the shoulder 41 of the metal rings 39, similarly to that shown in Figure 2. Finally a layer 46, consisting of an especially hard rubber, is applied over the entire unit. The assembled packer is then placed between steel holding plates and wrapped and finally cured so as to bond it to one integral unit. The surface of the packer may then be subjected to a final grinding process if desired.

The packers of my invention are highly resistant to oil especially when made of neoprene. They also resist high temperatures and in particular do not deteriorate under the influence of hot oil. Due to the use of harder rubber on the outside surfaces, the packers of my invention are highly resistant to abrasion. The packers are strong and durable and withstand a great many uses. While they are highly expansible in the lateral direction, they have a high degree of rigidity longitudinally. After cessation of compression forces applied to expand the packer into sealing position, they immediately return to their original shape and dimensions. Due to the specific shape of the metal reinforcing rings, a flow of rubber under the pressure used does not occur. All these features coact considerably to increase the service life of the packers of my invention.

It will be understood that while there have been described herein certain specific embodiments of my invention, it is not intended thereby to have the invention limited to the details given, since it is susceptible to various modifications and changes that come within the spirit of the disclosure and the scope of the appended claims.

I claim:

1. In an oil well packer a packer sleeve comprising an annular inner rubberized textile layer, an annular metal reinforcing ring member on each of the ends of said packer sleeve positioned over the ends of said inner textile layer, an annular bulk rubber layer between said metal reinforcing ring members co-axially arranged therewith and positioned over said inner textile layer, an outer annular rubberized textile layer extending over said bulk rubber layer and over said metal reinforcing ring members, and fastening means applied around said last-mentioned textile layer adjacent both ends of the sleeve and over said metal reinforcing ring members for securing said textile layer around said metal reinforcing ring members, all of said layers and members being integrally united.

2. In an oil well packer according to claim 1 wherein the fastening means comprises metal windings applied under tension over the ends of the outer textile layer.

3. In an oil well packer according to claim 1 wherein the rubber is a synthetic rubber-like material of the chloroprene polymer type.

4. An oil well packer comprising a sleeve having an annular inner rubberized textile layer, an annular metal reinforcing means in the form of a ring at each of the ends of the packer positioned over the ends of said inner textile layer,

an annular bulk rubber layer between said metal reinforcing means co-axially arranged therewith and positioned over said inner textile layer, an intermediate rubberized annular textile layer extending over said bulk rubber layer and over said metal reinforcing means, metal windings on said last mentioned rubberized textile layer adjacent both ends of the packer securing said textile layer around said metal reinforcing means, a rubberized textile material wound over said metal windings, and an outer annular rubber surface layer positioned over said intermediate textile layer and over the textile material wound over the metal windings, all of said layers and means being integrally united.

5. An oil well packer according to claim 4 wherein at least one of the textile layers comprises longitudinal members applied at an angle to the longitudinal axis of the packer sleeve.

6. An oil well packer according to claim 4 wherein at least one of the textile layers comprises rubberized cord.

7. An oil well packer according to claim 6 wherein the rubberized cord comprises synthetic fibers of the polyamide type.

8. An oil well packer according to claim 4 wherein at least one of the textile layers comprises a rubberized fabric.

9. An oil well packer comprising a sleeve having an inner annular rubberized textile layer, the annular metal reinforcing means on each of the ends of said sleeve positioned over the ends of said inner textile layer, an annular bulk rubber layer between said metal reinforcing means co-axially arranged therewith and positioned over said inner textile layer, an intermediate annular rubberized textile layer extending over said bulk rubber layer and over said metal reinforcing means, fastening means positioned over said intermediate textile layer adjacent both ends thereof securing said intermediate textile layer around said metal reinforcing means, an annular outer rubber surface layer over said intermediate textile layer, and a rubberized textile ring member positioned over the end edges of the concentric layers and the metal reinforcing means, all of said layers and means being integrally united.

10. An oil well packer according to claim 9 wherein the rubberized rings positioned at the ends of the packer sleeve comprise rubberized fabric.

11. An oil well packer according to claim 9 wherein at least one of said textile layers comprises rubberized fabric having cross threads considerably thinner than the longitudinal threads.

12. An oil well packer according to claim 9 wherein the rubberized textile ring at the ends of the packer sleeve are composed of rubberized cord.

13. An oil well packer comprising a packer sleeve having an inner annular rubberized textile layer, a metal ring in each end of said sleeve positioned over said inner textile layer at the ends thereof, each of said metal rings having a beveled surface at the inner end thereof and having an inwardly extending shoulder formed on the outer periphery adjacent the beveled end thereof, and each of said rings having a shoulder extension extending outwardly at the outer end of the ring opposite the beveled end, an annular bulk rubber layer positioned between said rings and over said textile layer, an intermediate annular rubberized textile layer extending over

said bulk rubber layer and over the shoulder formed at the beveled end of the ring and engaging said outwardly extending shoulder at the opposite end of the ring, clamping means wound under tension around the intermediate textile layer at the ends thereof applied between the inwardly extending shoulder at the beveled end of the ring and the outwardly extending shoulder at the opposite end of the ring, a reinforcing rubberized annular textile layer wound over said clamping means, and an annular outer rubber surface layer surrounding said last-named annular textile layer, all of said layers and means being integrally united.

14. An oil well packer comprising a packer sleeve having an inner annular layer consisting of a plurality of preshrunk fabric plies impregnated with a chloroprene polymer type synthetic rubber, said fabric being applied with the longitudinal threads at an angle of 45 degrees to the longitudinal axis of the sleeve and having cross threads which are considerably thinner than the longitudinal threads; an annular bulk layer of synthetic rubber of the chloroprene polymer type surrounding said inner layer of fabric plies and positioned thereover; two metal reinforcing rings, one on each end of said packer, said rings each being beveled at its inner end and each having an inwardly extending shoulder formed on its outer periphery adjacent the beveled end, and each ring having a projecting shoulder extension at the opposite end thereof; an outer annular fabric layer impregnated with a synthetic rubber of the chloroprene polymer type extending over said bulk layer and over said metal rings; steel wire windings on said outer impregnated fabric layer over said metal rings; annular fabric layers impregnated with synthetic rubber of the chloroprene polymer type over said wire windings; an outermost chloroprene polymer type synthetic rubber surface layer surrounding said outer fabric layer; annular fabric end members impregnated with synthetic rubber of the chloroprene polymer type positioned at both ends of said packer, said synthetic rubber used for said outer surface coat and for said fabric layers at the ends of said packer being harder than said synthetic rubber used for the inner parts of said packer; and means for anchoring said packer; all of said layers, rings and means being integrally united.

15. An oil well packer according to claim 14 wherein the fabric of which the inner and outer annular fabric layers and the fabric layer over the wire windings are composed, comprises synthetic polyamide textile fibers.

JOSEPH ROCKOFF.
